UNITED STATES PATENT OFFICE.

DAVID SMITH, OF AUBURN, NEBRASKA.

BARN-DOOR LATCH.

Application filed November 23, 1927. Serial No. 235,159.

This invention relates to door latches, and more particularly to a latch adapted for barns.

It has as its principal object the production of a latch that may be used with equal facility on either right or left hand doors, may be operated from either side of the door, and which offers no projections to catch and tear the harness of an animal passing through the door.

Another object is to provide a simple and efficient latch that can be manufactured cheaply.

With the above and other objects in view, the invention consists of certain novel constructions and arrangements of parts as will be hereinafter described and claimed.

In the drawing

Figure 1 is a perspective view of my latch in its relative position on a door and jamb shown by the dotted lines;

Figure 2 is a top view of the latch;

Figure 3 is a side view of the catch;

Figure 4 is a plan view of the blank for

forming the latch.

In carrying out my invention, I provide a U-shaped latch 1 formed of an elongated blank 2 of any suitable material, such as sheet or strap metal, which is bent backward at right angles at the spaced points 3 leaving a frontal portion or face 4 of a width substantially equal to the thickness of the door A. The ends 5 of the blank are provided with holes 6 for pivoting and between the points 7 and 8 at each end of the blank is drawn outward in an arcuate shape to form the handles 9. The frontal portion or face 4 has a square notch 10 cut out of its bottom edge at the center. This notch 10 is adapted to releasably engage the shoulder 11 on the catch 12. The said catch is a single piece of suitable material, as metal, having the countersunk holes 13 for attachment to the jamb B of the door frame, and having a sloping front edge or lip 14. In mounting the latch 1 on the door A, a bolt 15 is passed through the holes 6 in the ends

5 and through the door. This allows the opposite end of the latch 1 to be raised or lowered in a substantially vertical direction. 50 Any suitable stop 16 may be placed under the latch 1 so that in the locked position the bottom edge of the latch 1 will rest thereon. Immediately adjacent the notch 10 the said under side or under edge of the latch 1 is cut out so that from the points 3 at each side of the notch the bottom will have downwardly sloping edges 17 to the notch 10. The catch 12 is secured to the jamb B by screws 18 passing through the 60 catch.

It is obvious that as the door is shut, the free end of the latch 1 will strike the sloping front edge or lip 14 of the catch 12, raising the latch and causing the notch 10 to drop over the shoulder 11, thus locking the door.

While I have herein described a preferred embodiment of my invention, it is understood that I may vary from the same in minor details, within the scope of the appended claims.

I claim:

1. A barn door latch and catch, the latch being formed of a strip of metal bent U-shaped and so adapted to be set over the edge of the door and pivotally mounted thereon by the side portions of the latch, the bight of the latch having a notch cut out at its under edge; the catch being adapted to fasten to the door jamb and having a shoulder and lip adapted to engage the said notch of the latch portion.

2. The combination of a U-shaped door latch, the bight portion having a catch-notch cut at its lower edge, the stems thereof being curved outwardly to form handles, the extremities of the stems being adapted for passing to either side of the door for pivotal engagement therewith; and a catch adapted for positioning upon the door jamb for engaging the said latch at the catch-notch.

In testimony whereof I affix my signature.
DAVID SMITH.
